UNITED STATES PATENT OFFICE.

ERIK A. ASPLUND, OF WAUKEGAN, ILLINOIS.

REMOVER FOR FRUIT-JAR CAPS AND THE LIKE.

1,402,731.

Specification of Letters Patent. Patented Jan. 10, 1922.

Application filed March 16, 1921. Serial No. 452,791.

To all whom it may concern:

Be it known that I, ERIK A. ASPLUND, a citizen of Finland, residing at Waukegan, in the county of Lake and State of Illinois, have invented certain new and useful Improvements in a Remover for Fruit-Jar Caps and the like, of which the following is a specification.

This invention relates to improvements in a device to be used for frictionally gripping the caps of fruit jars, bottles and the like, for the purpose of rotating them in either direction with respect to the jar, to the end that the caps may be tightened thereon or removed therefrom.

One of the objects of the invention is to provide a device of the above mentioned general character, which shall be simple and inexpensive in construction, strong, durable and efficient in operation, with its parts so arranged that the handle members of the device will always be located in such relation to one another as to be controlled or gripped by one hand only of the user, that is, so that the handles of the device will not become separated at a distance greater than the span of one hand and so that when the handle members are closed against each other they can be separated by the employment of one hand only to a sufficient degree to allow the curved clamping or gripping members to be placed around the cap.

Another object of the invention is to provide a cap gripping and rotating device of such construction that it, when in operative position on a cap, will overlie or engage that portion of the cap above the screw-threads thereon which co-operate with screw-threads on the mouth of the jar or bottle, thus preventing the screw-threads of the cap being pressed into closed engagement with the screw-threads of the jar or bottle by the instrument when the same is applied to the cap.

A still further object is to provide a cap remover adapted for frictionally engaging the caps of jars or bottles of different sizes.

Other objects and advantages of the invention will be disclosed in the subjoined description and explanation.

In the accompanying drawing which serves to illustrate an embodiment of the invention—

Fig. 1 is a plan view of the device showing it in operative position on the cap of a jar.

Fig. 2 is a horizontal sectional view through the remover taken on line 2—2 of Fig. 1.

Fig. 3 is a similar view taken on line 3—3 of Fig. 1 showing the application of the device to the cap of a bottle.

Fig. 4 is a sectional view of the handle members of the device taken on line 4—4 of Fig. 1.

Fig. 5 is a fragmental inner face view of one of the handle members taken on line 5—5 of Fig. 1, and

Fig. 6 is a fragmental plan view showing a modified form in the construction of the clamping portions of the device.

Like numerals of reference refer to corresponding parts throughout the different views of the drawings.

The reference numeral 7 designates the cap of a fruit jar, which is provided as usual around its periphery with screw-threads 8 to engage co-operating screw-threads on the exterior of the neck or mouth of a fruit jar. As is well known, these screw-threads terminate at their upper ends a slight distance below the upper surface of the cap 7 resulting in an annular wall 9 at the upper portion of the cap.

To take advantage of this formation of fruit jar caps 7, as well as the bottle caps 10, (which are of substantially the same construction) see Fig. 3, is one of the features of my invention.

As shown in Fig. 1, the wrench or remover consists of a pair of oppositely curved gripping members 11 and 12 which are substantially angular in cross-section as shown in various views of the drawing. At one of their ends the members 11 and 12 are pivotally connected together and have their depending flanges 13 cut away as at 14, see Fig. 1. One of the members, for instance the member 12, overlaps at its pivoted end the corresponding end of the member 11, 100 which latter member has on its pivoted end an extension or arm 15 located in the cut-away portion 14 of the depending flanges 13 and adapted when the clamping members 11 and 12 are moved from each other, to 105 abut against the end of the flange 13 adjacent the cut-away portion 14 thereof, and thus restrict or prevent further outward movement of said gripping or clamping members.

Each of these members has extended from the end of its curved portion opposite its

110

pivoted end a handle member 16 each of which is substantially angular in cross-section as is clearly shown in Figs. 3 and 4 of the drawings. Outwardly of but near the 5 juncture of the handle members 16 with the members 11 and 12 each of said handle members has its downwardly extended flange 17 provided with an outwardly and longitudinally curved inner face as at 18, which faces 10 are provided with vertical serrations 19, see Fig. 5, to engage a cap 10, such as that of a bottle or of a container of such diameter that the gripping members 11 and 12 would not co-operate with to grip the cap. From 15 the above, it will be understood that the handle members as well as the gripping members 11 and 12 are substantially angular in cross-section with their angles presented towards each other, thus producing 20 or affording an upper or overlying flange 20 to rest on the top of the cap when the device is in operative position thereon, which arrangement will so locate and maintain the depending flanges 13 of the members 11 and 12 so that they will, when the 25 handles 16 are pressed together, grip the vertical wall or upper portion 9 of the jar of the cap as will be readily understood by reference to Fig. 2 of the drawing.

30 In applying the device to a bottle cap 10, as shown in Fig. 3, it is evident that the curved inner faces of the depending flanges 17 will engage the upper portion 9 of the cap above the screw-threads 8 thereon and 35 thus prevent said threads being injured or pressed tightly on the co-operating threads on the neck of the bottle. A further advantage in forming the handle members with the depending flanges 17 is, that after 40 the device has been removed from a cap and the handle members thereof are located closely together, they can readily be separated by the use of one hand only of the user, by simply grasping the handle members and placing the fingers between the 45 flanges 17 when said handle members can be separated thereby by forcing one of the handle members from the other until the arm 15 on the pivoted end of one of the 50 gripping members shall engage the adjacent end of the other gripping member, which operation will restrict the movement of the handle members to such an extent as to permit them being spanned and grasped 55 with one hand. When in the last named position, the gripping members 11 and 12, as is obvious, are in position to be placed on the cap of a jar so that their overhanging flanges 20 will lie on the top of said cap, 60 when by forcing the handle members 16 towards each other, great gripping force may be applied to the cap for turning the same

in the proper direction to tighten it on the jar or remove it therefrom.

In Fig. 6, I have shown a modification in 65 the construction of the device, which consists in making the gripping members 11 and 12, as well as the handle members 16, of a single piece of material. In this modified construction, instead of pivotally connecting the gripping members 11 and 12 together at their ends opposite the handle members 16, said ends are joined by a flexible portion 21 which is an integral part of said members, which construction, it is obvious, 75 will permit the gripping or clamping members 11 and 12 to be sprung into contact with the cap which they surround, when the handle members 16 are pressed towards each other.

Having thus fully described my invention, what I claim as new and desire to secure by Letters Patent is—

1. A device of the class described, consisting of a pair of oppositely curved and 85 handled clamping members pivotally connected together at one of their ends, said clamping members being in cross-section substantially angular in shape providing an overhanging and depending flange on each 90 to respectively rest on the top and frictionally engage the upper portion of the wall of a cap, the depending flanges of said members terminating at a distance from the pivot of said members, and an arm extended 95 from the pivot of one of said members outwardly and adapted to contact with the adjacent end of the depending flange of the other of said members to restrict the outward movement of the clamping members. 100

2. A device of the class described, consisting of a pair of oppositely curved and handled clamping members pivotally connected together at their ends, said clamping members each having a depending flange at 105 its pivoted portion and each of the handles of said members being substantially angular in cross-section thereby providing an overhanging and depending flange on each 110 handle to respectively rest on the top and frictionally engage the upper portion of the wall of a cap, the inner faces of the depending flanges of the handles being provided with longitudinally and outwardly curved coinciding portions to form a seat 115 for the reception of a bottle-cap and the like, and an arm extended from the pivot of one of the oppositely curved members outwardly and adapted to contact with the adjacent end of the depending flange of the 120 other of said curved members to restrict the outward movement of said members.
